(57) **CLAIM**

The ornamental design for a light emitting diode lamp, as shown and described.

DESCRIPTION

FIG. 1 is a perspective view of a light emitting diode lamp showing the new design;

FIG. 2 is a front view thereof;

FIG. 3 is a rear view thereof;

FIG. 4 is a right side view thereof, the left side view being a mirror image thereof;

FIG. 5 is a top view thereof;

FIG. 6 is a bottom view thereof; and,

FIG. 7 is a cross-sectional view taken along line 7—7 in FIG. 2 with the internal parts omitted, wherein the portions having the double slanted lines are transparent.

The front surface of the transparent portion is processed by satin frosting except the three circular regions shown in FIG. 2.
